LIGHTING FIXTURE

Filed April 2, 1929

FIG. 1

FIG. 4

FIG. 2

INVENTOR:
EDWARD J. RUETH

By his aff'c

UNITED STATES PATENT OFFICE

EDWARD J. RUETH, OF CLEVELAND, OHIO

LIGHTING FIXTURE

Application filed April 2, 1929. Serial No. 351,856.

My invention pertains to a light fixture. The adaptation of the invention exemplified by the drawings shows its use in association with an electric lamp socket.

My long experience with the lighting fixture industry caused me to become familiar not only with marketed constructions, but also with a series of patented forms including those illustrated in Andersen No. 1,114,571, Andersen No. 1,171,013, Harris No. 1,332,214, Wanbaugh No. 1,495,826 and Robinson No. 1,588,267.

One object of my invention has been to design a screwless fixture. Another object is to provide a fixture with a lower end of its globe suspending holder so narrowed in one dimension that relatively transverse projections intended actually to support the globe, may be successively inserted into the neck of the globe preparatory to having the globe gravitationally suspended thereon. Further objects have been to contrive a duplex provision against undesirable displacement of a cover either upwardly or turnably and incidentally so that the means for preventing displacement of the cover upwardly necessarily causes the cover to limit a lifting displacement of the globe from the holder. A general object has been the design of a lighting fixture which combines intrinsic merit with commercial merit, in the sense, that it is easy to assemble and adjust so that it will effectively exercise its function while including, apart from a standard type of electric socket and globe, only two stamped pieces which are simple and economical of manufacture.

It is to be realized that the scope of my invention comprehends many equivalent constructions. The showing of the drawing and the particular description are merely a specific exemplification of a plurality of mechanical embodiments and arrangements.

Adverting to the drawing:

Figure 1 is a side elevation of an improved lighting fixture embodying my inventions, partly broken away to show certain details in axial section.

Figure 2 is mainly a vertical section on line 2-2 of Figure 1 partly shown in elevation.

and with two elements additionally shown in altered positions by dot and dash lines.

Figure 3 is a horizontal section on line 3-3 of Figure 2 looking upwardly as indicated by the arrows.

Figure 4 is a plan view on reduced scale of one part.

As illustrated, the fixture is rigidly secured in any appropriate manner to a ceiling 1 and comprises adjacent thereto a hollow metal stamping 2 which is integrally constricted in a downwardly direction at 3 and then again widened or flared at 4. Where the sections 3 and 4 merge the primary support 2 is provided interiorly with an apertured partition 5, against opposite sides of which a two-part electric light socket 6 is clamped. The two parts of the socket 6 may be in screw threaded connection with each other, but since that type of connection is common in the art it has not been illustrated. An incandescent lamp 7 is detachably secured in the socket 6.

Continuing downwardly the lower end of the section 4 is flanged, but instead of being annular it is designed, as shown in Figure 3, to comprise two concentric diametrically opposite arcuate portions 8 and two diametrically opposite straight and parallel portions 9 to constitute one of the features of my invention. It is interpolated that the horizontal cross-sectional shape of the fixture is of no consequence and that while it is shown of mainly circular cross-section, for the purpose of economy in commercial production, it might be of any desired polygonal shape. Since fixtures are, however, usually round, my provision of one or more flat portions 9 does constitute a feature of highly meritorious consequence. Premising association with a round fixture, the number of flat portions 9 of the depending flange is manifestly variable at the will of the manufacturer with consideration of cost. As exemplified, the two flat portions 9 are each fashioned midway with an outwardly projecting burr 10 to serve the purpose of a yielding detent or catch, as will be hereinafter explained. The burrs 10

might instead, or additionally, be provided

on the arcuate portions 9 of the depending flange.

Continuing from the lower end of the depending flange composed of the portions 8 and 9 the support is likewise of unsymmetrical design, circumferentially regarded, and immediately adjacent its lower end is fashioned as an endless enveloping ledge 11. Alongside of the straight portions 9 the ledge is narrower by reason of truncation along the diametrically opposite lines 12 of the entire lower end of the support, which latter has in consequence an oblong or inverted T-shape so narrowed in one dimension that relatively transverse projections may be successively inserted into the neck of a globe preparatory to having the latter gravitationally suspended thereon. The outward borders of the wider and arcuate diametrically opposite portions of the ledge merge with two depending somewhat longer flanges 13 which terminate as outwardly flared ledges 13^a, upon which opposite sides of the constricted neck 14, of a globe 15, may rest when the upper end of the globe is caused partially to enclose the flanges 13 successively as suggested by the upper end of the globe's dotted line position in Figure 2. The upper rim 16 of the neck of the globe may be optionally shaped as shown.

Functioning so as to accomplish a realization of certain outstanding advantages of my invention, is a round cover 17, which includes a flat top 17^a fashioned with a central opening 18 corresponding in shape and nearly in size to the plane figure defined by the flange composed of the two portions 8 and the two portions 9. Accordingly, as shown in Figure 4, the opening 18 is defined by two opposite arcuate edges 19 and by two opposite straight edges 20, the edges 19 being adapted to be juxtaposed to the curved portions 8 and the edges 20 to the straight portions 9 respectively. By this arrangement when the cover 17 is in the position shown in Figure 1 its turning movement will be prevented by reason of the juxtaposed flat surfaces, as will be readily understood. Prior to seating that portion of the top of the cover, which borders its peculiar opening 18, upon the ledge 11 its edges 20 must be sprung over the burrs 10, which, because of the resiliency of the metal, will yield slightly in an inward direction and afterwards again spring out, as appears in Figure 1, thereby preventing upward displacement of the cover until so manipulated. The border of the cover top continues downwardly as a short flange 21 thence outwardly as a narrow ledge 22 adapted to rest on the rim 16 of the globe and thence again downwardly as a longer flange 23, which very closely approaches or may alternatively contact the top of the globe when the cover top rests upon the ledge 11. In this manner the emplaced cover additionally serves to resist

upward tilting of the globe and certainly to prevent a tilting to such an extent as would permit its detachment from the ledge 13^a.

My lighting fixture is of outstanding simplicity, not only as to structure and number of parts, but in respect to its functioning assembly. While the globe 15 is being mounted in place, as indicated by its broken line position in Figure 2, the cover may be lifted to some non-interfering position, as for instance, to that indicated by the broken lines which, in Figure 2, define its outline.

I claim:

1. In combination, a globe having a constricted open end, a holder including circumferentially spaced flanges insertible in and adapted to support said globe, said holder being fashioned intermediately of its ends with a substantially vertical flat surface, and a cover adapted to rest upon said globe and provided with an opening intersected by said holder and having its margin partially defined by a flat surface juxtaposed to the flat surface of said holder when the cover rests upon the globe.

2. In a lighting fixture, a holder, said holder being fashioned intermediately of its ends with a substantially vertical flat surface, a cover provided with an opening intersected by said holder and having its margin partially defined by a flat surface juxtaposed to the flat surface of said holder when the cover rests upon the globe and means comprising a yieldingly engageable projection on one of said flat surfaces for resisting displacement of said cover.

3. In a lighting fixture, a holder, a cover provided with an opening intersected by said holder, means consisting of juxtaposed flat surfaces on said holder and cover respectively for preventing relative turning movement and means including a yieldable catch on said member adapted to be contacted by the edge of the opening in said cover for deterring upward movement of the latter.

4. In an article of the character described, the combination of a vertically disposed holder and a cover provided with an opening loosely intersected by said holder, said holder and the margin of the opening in said cover each including a straight side, said straight sides adapted for juxtaposition to prevent a relative turning movement.

5. In an article of the character described, the combination of a round tubular holder fashioned near its lower end with two oppositely disposed flat sides and a cover provided with an opening loosely intersected by said holder, the margin of the opening in said cover including two oppositely disposed straight sides adapted for juxtaposition with said flat sides to prevent a relative turning movement.

6. In an article of the character described, the combination of a vertically disposed

holder fashioned near its lower end with a flat side and a cover comprising an endless depending flange and a top provided with an opening corresponding in shape to the flat-sided lower end of said holder and loosely intersected by the latter, said holder being provided downwardly beyond its flat side with a ledge adapted to limit the downward movement of said cover while enveloping said holder.

10 7. In combination, a globe having a constricted open end, a vertically disposed holder having its lower end fashioned with a flat side and with its transverse dimensions being larger and smaller respectively than said open end of the globe and a cover comprising an endless depending flange and a top provided with an opening corresponding in shape to the flat-sided lower end of said holder and loosely intersected by the latter, said cover flange being adapted gravitationally to rest upon said globe and the flat sides of said holder and of the margin of the cover opening being juxtaposed when the lower end 25 of said holder is inserted in and suspends the latter.

8. In a lighting fixture, a flat-sided holder, a cover provided with an opening including a flat-sided edge whereby to prevent relative 30 turning movement and yieldable means for resisting relative displacement of said holder and cover in a different manner.

Signed by me, this 22nd day of March, 1929.

EDWARD J. RUETH.
